UNITED STATES PATENT OFFICE

RALPH H. GREEGOR, OF COLUMBUS, OHIO, ASSIGNOR TO THE KINNEAR MANUFACTURING COMPANY, OF COLUMBUS, OHIO, A CORPORATION OF OHIO

TROLLEY BRIDGE

Application filed December 30, 1927. Serial No. 243,740.

This invention relates to bridges for the trolleys of electrically propelled vehicles, and is especially useful in connection with street railway car barns equipped with rolling doors. The principal object of the invention is to provide an improved construction whereby when the door is rolled up to its normally open position the bridge is placed in its functioning position and when the door is sufficiently unrolled from its normal position the bridge is removed from bridging position, or generally the position of the door automatically controls the position of the bridge. Other objects of the invention will appear from the disclosure herein.

The invention is embodied in the example herein shown and described, the features of novelty being finally claimed.

In the accompanying drawing—

20 Figure 1 is a transverse vertical section through the wall and lintel of a car barn doorway showing the invention applied thereto with the rolling door about to raise the trolley bridge to its bridging position.

25 Fig. 2 is a similar view showing the door further raised, or, to say normal position and the bridge in bridging position.

Fig. 3 is a detail view, on a larger scale, of the bridge and the seat for its free end, the 30 parts being in the position shown in Fig. 1.

Fig. 4 is a similar view, the parts being in the position shown in Fig. 2.

Fig. 5 is a plan view of the parts as seen in Fig. 4.

35 Fig. 6 is a section on a larger scale on the line VI—VI Fig. 4.

Fig. 7 is a similar section on the line VII—VII Fig. 4.

40 Fig. 8 is a detail on a larger scale of the trolley wire and by pass wire connections with the track section.

In the views 10 designates the lintel of a car barn doorway there being installed in the wall above said lintel at its inner side a flexible rolling door 11 adapted to be wound up and unwound from a roller or shaft 12 mounted in supporting end brackets like that at 13, as usual in such structures and now in common use. In the present instance, however, the bottom bar 14 of the door has secured

to it a tripping lug 15 of sufficient width placed to strike an arm or trip connected with the bridge when the door is raised, the bridge itself being struck by the bottom bar to remove it from bridging position when the door is lowered as will hereinafter further appear.

55 The trolley wire or power line has terminals 16 and 17 externally and internally respectively of the barn that are electrically connected by a line 18 carried upward 60 through the wall of the building above the rolling door and momentum of the car is relied on to carry the trolley under the lintel and across the bridge.

Between the terminals 16 and 17 of the 65 trolley wire are suitably supported insulated trolley track sections 19 and 20 of wood seated in wooden bodies, as at 21, 21^a, the former at the lower end of a bracket 22 secured to the inner side of the building wall and the latter 70 by suitable bolts to the lintel members.

75 Supported by a pivot shaft in a bracket 23 set in the wooden body 21^a is the track member 24 for bridging the gap between the interior and exterior track sections 19 and 20. One end of the shaft of said pivoted bridging member has secured to it a trip arm 25 standing at an angle of approximately sixty degrees to the bridging member; and also secured to said shaft is a weight 26, a 80 part of which can be made of lead secured to a part of harder material, said weight having its center of gravity about ninety degrees from the trip arm so that said bridging member can be thrown to stand yieldingly in a poised vertical position as shown in Fig. 1 or in an unpoised horizontal position as shown in Fig. 2, a suitable stop being provided to hold the bridging member in said horizontal position. The stop for the free 85 end of the bridging member when in horizontal position is a socketed metallic piece 27 bolted to the wooden base 21. The bridging member is held in poised vertical position by the balancing weight 26. When the 90 bridging member is in vertical position, as shown in Figs. 1 and 3, the tripping arm 25 lies in the path of movement of the lug on the door and when the weight is swung so 95 that its center of gravity is thrown suffi- 100

ciently to the opposite side of the vertical line of the axis of the bridging member the latter member is thrown into bridging position. In this last described position of the bridging member it is alined with the track sections 19 and 20 and the car trolley can ride, by momentum of the car on, and be guided by, said bridging member from one terminal of the trolley wire into or out of the barn and onto the other terminal of the trolley wire from which propelling current is again taken. When the door is lowered the bottom bar thereof strikes the bridging member and swings it downward sufficiently to permit it to assume the vertical position or approximately as indicated in Fig. 1. The bridging member, and its stop, which are shown as of metal are, of course, insulated from the trolley wires.

20 The forms of the parts can be changed without departing from the gist of the invention as claimed.

What I claim is:

1. In combination with a structure having an opening, a door for said opening adapted to be raised and lowered, an electric power line having terminals at each side of the plane of movement of said door, a pivoted non-conducting trolley bridging member between said terminals, means on said door for causing said bridging member to assume trolley-guiding position when the door is raised to normally open position and for removing said bridging member from that position when the door is lowered from normal raised position and a weight operating on the bridging member for holding it in bridging position independently of the door.

2. In combination with a building having a door opening and door guiding means, a door movable in said guiding means for opening and closing said door opening, an electric power line having terminals at opposite sides of the plane of movement of said door, a trolley bridging member pivoted to the building at one side of the door opening to bridge the space between said terminals and across the plane of movement of the door, an arm operatively connected with said bridging member for actuating the bridging member, said arm being shorter than the bridging member and located wholly at one side of the plane of movement of the door, means on said door for actuating said arm to cause the bridging member to assume trolley guiding position when the door is moved to normally open position and for actuating said bridging member to remove it from bridging position when the door is moved from normally open position, and a weight connected with the bridging member for holding it in bridging position independently of the door and also adapted to hold the bridging member and said actuating arm in position for actuation by the actuating member on the door when the latter is moved from closed position to normally open position.

RALPH H. GREGOR.

member on the door when the latter is moved from closed position to normally open position.

3. In combination with a building having a door opening and door guiding means, a door movable in said guiding means for opening and closing said door opening, an electric power line having terminals at opposite sides of the plane of movement of said door, a trolley bridging member pivoted to the building at one side of the door opening to bridge the space between said terminals and across the plane of movement of the door, an arm operatively connected with said bridging member for actuating the bridging member, said arm being shorter than the bridging member and located wholly at one side of the plane of movement of the door, means on said door for actuating said arm to cause the bridging member to assume trolley guiding position when the door is moved to normally open position and the arm-actuating means thereon beyond said arm, and for actuating said bridging member to remove it from bridging position when the door is moved from normally open position, and a weight connected with the bridging member for holding it in bridging position independently of the door and also adapted to hold the bridging member and said actuating arm in position for actuation by the actuating member on the door when the latter is moved from closed position to normally open position.

RALPH H. GREGOR.
